ATTORNEY.

UNITED STATES PATENT OFFICE.

ALBERT J. FANDREY, OF INDIANAPOLIS, INDIANA.

DUST-ARRESTER FOR RADIATORS.

1,019,143.

Specification of Letters Patent.

Patented Mar. 5, 1912.

Application filed June 21, 1911. Serial No. 634,635.

To all whom it may concern:

Be it known that I, ALBERT J. FANDREY, a citizen of the Empire of Germany, subject of Emperor William II, and resident of Indianapolis, county of Marion, and State of Indiana, have invented a certain useful Dust-Arrester for Radiators; and I do hereby declare that the following is a full, clear, and exact description thereof, reference being had to the accompanying drawings.

10 The object of this invention is to provide a suitable dust collector for radiators which will separate the dust from the current of heated air rising from the radiator and prevent the walls from being soiled thereby.

15 The feature of the invention lies in a supporting frame, which may be adjusted to suit the piping installation, and an air strainer or dust collector resting thereon of such a fabric as will permit the passage of air through it and of such a shape as may be easily replaced when soiled.

20 The nature of the invention will be understood from the accompanying drawings and the following description and claim.

25 In the drawings Figure 1 is an end elevation of a radiator with the device installed thereon. Fig. 2 is a front elevation of the device removed from the radiator. Fig. 3 is a vertical transverse section on the line 3—3 of Fig. 2. Fig. 4 is a vertical longitudinal section on the line 4—4 of Fig. 3. Fig. 5 is a perspective view of the supporting frame with the cover removed.

30 In detail there is shown in the drawings a box-like wire frame 10 of rectangular cross section. Said frame is open at the bottom and in width is substantially twice its depth and is of such dimensions as will permit its 35 being easily slipped over the top of a radiator where it may be supported by the hooks 12 engaging the end sections of the radiator. An extension 13 from one side projects below the main frame a distance substantially the 40 depth of the frame and in use is bent rearwardly sufficient that the extension will touch the wall behind the radiator, as shown in Fig. 1. The hooks 12 mentioned are also

formed of wire doubled and bent into a V-shape, the looped end of the wire forming the point of the hook and the ends of the wire bent around the lower end wire 14 in such a manner that the hooks may turn about said wire and have the bent portion of the hooks extending downward and inwardly when said hooks are thrown against the inner end of the frame.

45 Before the frame 10 is placed on the radiator a fabric covering 15 is placed upon it. Said covering is of scrim or other goods, preferably cotton, of a fairly open weave and closely fits the frame and has a flap-like portion which covers the extension 13 of the frame. Thus it will be seen that when installed on a radiator all the air heated by the radiator in rising from the top of the radiator must pass through said fabric and leaves its dust on the fabric.

50 While the drawings illustrate a dust collector which is rectangular in construction, it is not desired to limit my invention to this particular construction as it may be made with a semi-cylindrical top or, in fact, any desired shape to fit a radiator top.

I claim as my invention:

55 A dust collector for a radiator consisting of wires forming a substantially rectangular skeleton frame with the underside open and adapted to envelop the top of a radiator and with a downwardly and outwardly inclined extension from the lower edge of one side of said frame, a reticulated fabric covering the top and sides of said skeleton frame, and upwardly extending hooks connected with the lower part of each end of said frame adapted to engage the top of the end sections of the radiator for supporting the frame.

60 In witness whereof, I have hereunto affixed my signature in the presence of the witnesses herein named.

ALBERT J. FANDREY.
